UNITED STATES PATENT OFFICE.

HENRY F. SAMSTAG, OF NEW YORK, N. Y.

DESIGN FOR A DOLL.

● 40,986.

Specification for Design.

Patented Nov. 8, 1910.

Application filed August 27, 1910. Serial No. 579,352. Term of patent 3½ years.

To all whom it may concern:

Be it known that I, HENRY F. SAMSTAG, a citizen of the United States, residing in the borough of Manhattan, city, county, and State of New York, have invented a new, original, and ornamental Design for a Doll, of which the following is a specification, reference being had to the accompanying drawings, forming part thereof.

The figure illustrated is a front elevation of my design.

I claim:

The ornamental design for a doll, as shown.

HENRY F. SAMSTAG.
